UNITED STATES PATENT OFFICE.

JAMES MORGAN, OF WEST PHILADELPHIA, PENNSYLVANIA.

TONGS.

SPECIFICATION forming part of Letters Patent No. 732,100, dated June 30, 1903.

Application filed October 11, 1902. Serial No. 126,917. (No model.)

To all whom it may concern:

Be it known that I, JAMES MORGAN, a citizen of the United States, residing at West Philadelphia, in the city of Philadelphia and State of Pennsylvania, have invented a new and useful Improvement in Tongs, of which the following is a specification.

My invention is an improvement in tongs, and has for its object to provide a convenient and handy device of this character which can be used for a variety of objects and which will be adapted for work where a tighter grip is required than can well be had with tongs of the ordinary construction.

The several features of my invention are described in the following specification and shown in the accompanying drawings, in which—

Figure 1 is a perspective view of a pair of tongs adapted for plumbers' use. Fig. 2 is an enlarged detail view, partly in section. Fig. 3 is a section drawn through one of the legs of the tongs. Fig. 4 is a modification showing the device adapted for use as a fruit-picker.

In carrying out my improvement I utilize a circular base-plate A, centrally perforated and having an integral upwardly-extending sleeve A¹, laterally slotted at A² and open at each end. An annular flange A³ terminates the upper end of the sleeve. Sliding in this sleeve and extending both above and below it is the rod B, threaded in its upper portion. At its upper end the rod carries a cap B' and ring B², and a fly-nut B³ works on the threaded part of the rod.

The plate A carries two oppositely-disposed pairs of lugs A⁴, and pivoted between each pair of lugs is a tong-leg C. Midway the length of these tongs a shoulder C' is formed, and the inner face of the tongs is recessed adjacent the shoulder, as shown at C². Below the shoulder the tongs are concave in cross-section, as shown at C³, Figs. 1 and 3. A toggle-joint D is pivotally connected to the lower end of the rod B and also pivotally connected through the link members D' to the tongs C at the recesses C². The rod B is recessed at B⁴, said recess being adapted to register with the slot A², and a spring B⁵ is secured in said recess.

In Fig. 4 I have shown a somewhat similar

construction, the fly-nut being omitted, and at the ends of tongs E are positioned baskets E', formed of wire network and braced by 55 the ring E² and arc E³. A cutting-blade E⁴ is formed at the upper side of each ring. The operation of this device will be readily seen from the drawings.

The operation of my improved tongs is as follows: The spring B⁴, projecting through the opening A², will hold them in a closed position, so that when carried by the ring the tongs will not fly apart nor strike together. By pressing in the spring and pushing the 65 cap toward the sleeve the rod will slide inward, forcing the tongs apart by means of the toggle-joint D. By pulling on the ring the tongs will be drawn together, and by turning the fly-nut down against the flange A³ 7c considerable gripping force may be secured.

Having thus fully described my invention, what I claim as new, and desire to secure by Letters Patent, is—

1. The combination with a circular, perforated plate, a sleeve carried on the plate and laterally slotted, a rod threaded at its upper end adapted to slide through the sleeve and plate, a spring carried by the rod and adapted to engage the slotted portion of the sleeve, 75 tongs pivoted to the plate, and a toggle-joint connecting the lower end of the rod and the tongs.

2. The combination with a plate having an opening and a slotted sleeve carried by said 85 plate, of tongs pivoted to the plate, a rod passing through said plate and sleeve, and having its upper end screw-threaded, a link connection between the lower end of the said rod and tongs, a nut on the screw-threaded 90 end of rod, and a catch connecting said rod and sleeve.

3. The combination with a plate having an opening and supporting a slotted sleeve, of tongs pivoted to said plate, a rod passing 95 through said plate and sleeve, a link connection between said rod and tongs and a catch on the rod to engage the slot in the sleeve to lock the tongs in a closed position.

JAMES MORGAN.
